UNITED STATES PATENT OFFICE.

GLEN WILLIAM BAIRD AND ARTHUR LAMB, OF DRUMMOND, IDAHO.

MOTOR-DRIVEN TOOTHBRUSH.

Application filed August 18, 1924. Serial No. 732,799.

This invention relates to improvements in power driven tooth brushes.

The primary object of this invention is the provision of an electrically operated tooth brush embodying novel means for reversibly driving a brush head.

A further and important object of this invention is the provision of a novel type of electrically operated tooth brush, embodying a brush head and means for reversibly driving the same in either direction at varying speeds.

A further object of this invention is the provision of an improved tooth brush embodying a brush head which may be driven continuously in either direction about its axis.

A further object of this invention is the provision of a power driven brush including a novel change speed device which may be used to perform the dual function of changing the speed of rotation of a brush, or of reversing the direction of drive thereof.

Other objects and advantages of this invention will be apparent during the course of the following detailed description.

In the accompanying drawing, forming a part of this specification, and wherein similar reference characters designate corresponding parts throughout the several views.

Figure 1 is a side elevation, partly in section, of the improved power driven brush showing details thereof.

Fig. 2 is a fragmentary plan view of the improved tooth brush structure, showing the associated details thereof.

Fig. 3 is a fragmentary sectional view of a portion of the change speed and reversing mechanism.

Fig. 4 is a cross sectional view taken through a guard or shield member provided for a brush head and showing the latter in associated relation.

In the drawing, wherein for the purpose of illustration is shown only a preferred embodiment of the improved power driven tooth brush, the letter A may generally designate the improved power driven tooth brush, which may include a base B, upon which a motor C is mounted for the operation of a driven shaft D; the latter being connected as by speed changing and reversing mechanism E to the motor details. A brush head F may be provided, of a novel

detachable type, which may be associated with means G for connection with driven shaft D.

The base B is preferably flat, and preferably elongated, at one end having the motor C supported thereon as by legs 15, 60 either rigidly or integrally connected with the base B, so that the vertically disposed drive shaft 18 of the motor extends below the motor housing and has a drive wheel or pinion 19 connected thereon, which may be 65 of the friction gear type. The drive gear 19 is, of course, disposed in a horizontal plane, parallel and just spaced above the top surface 20 of the base B. A suitable flexible conduit 21 may lead off from the motor 70 housing, through which the conducting cables are disposed to the interior of the motor.

At the end of the base B, opposite from the motor C, a standard 25 is supported in 75 vertical manner, preferably integral with the base B, which intermediate its ends is provided with an opening 26 within which a bushing 27 fits for rotatably receiving the cylindrical shaped forward end 29 of the 80 driven shaft D.

The driven shaft D is of novel construction, including the end 29 above mentioned, while adjacently connected to the bearing end 29 is a positioning flange 30 adapted to 85 abut the rear edge and surface of the bushing 27 and standard 25. A polygonal shaped body portion 31 of the driven shaft D extends rearwardly on a horizontal axis, and at its extreme rear end is provided with a 90 reduced portion 33 which is journaled within a suitable bearing extension 35 provided on the motor housing.

This body portion 31 of the driven shaft D is preferably triangular in cross section, 95 and slidably receives details of the speed changing and reversing mechanism E which will be subsequently described.

The base B between the standard 25 and the motor C preferably has an opening 38 100 therein within which an anti-friction bearing or bushing structure 39 is mounted, to rotatably receive a stub shaft 40 of a large driven gear 41, preferably of the metal disc type, which is fixed with the stub shaft 40 105 and disposed in a horizontal plane over the base B, so that the outer periphery thereof is in frictional driving contact with the outer

periphery of the motor driven friction gear 19.

Referring to the change speed and reversing mechanism E by which the shaft D may be driven in either direction about its axis, at various speed ratios, this means E preferably includes a gear wheel structure 50, mounted on the drive shaft D for longitudinal movement along the polygonal cross section portion 31. This wheel structure 50 includes the central metal portion 51 provided with a polygonal opening 52 therein for slidably receiving the portion 31 of the shaft D therethrough, and furthermore includes the ring shaped resilient wheel portion 55, preferably of rubber which is supported between flanges 56 and 57 rigid with the central portion 51, and which resilient portion 55 is in sliding engagement at its outer periphery upon the top surface 58 of the large wheel 41.

Means is provided to shift the wheel structure 50 along the shaft portion 31, which includes a rod 60 mounted on a horizontal axis 25 within a passageway 61 at the top of the standard 25, and which at its rear end is downturned, at 62, and providing the bifurcated lower end 63 which is splined upon the portion 51 of the sliding wheel 50, and 30 by means of which the wheel 50 may be slid as the rod 60 is drawn through the opening 61 in the top of the standard 25. Means is of course provided for holding the wheel in a determined location, and this means includes a plurality of notches 65 formed at various spaced intervals along the top edge 66 of the rod 60, and into which the back end 66 of a resilient spring 67 may snap to hold the rod in a predetermined position. Spring 40 67 is, of course, resiliently mounted at its forward end by means of a set screw 69, upon the top of the standard 25. The rod 60 extends forwardly of the standard 25 and has a finger engaging knob 75 thereon.

From the foregoing description it is apparent just how the driven shaft D may be operated. When the wheel structure 50 is most forwardly positioned on the shaft body 31, the wheel 50 will be in engagement with the top surface of the motor driven wheel 41, at one side of the axis of said motor driven wheel 41, and as the wheel 50 is moved by the means E forwardly and towards the axis of the rotating wheel 41, it is readily apparent that the speed of the shaft D will decrease. As the wheel 50 moves across the axis of rotation of the wheel 41 the drive of the shaft D will be negligible, and after it has passed this axis in a forward direction 50 the wheel 50 will be driven in a reverse rotation for driving the driven shaft D likewise in a reverse rotation. Thus, by placing the wheel 50 at the desired side of axis of rotation of the wheel 41, the driven shaft D 60 may be driven in the desired direction, and

the speed ratio thereof may be varied by moving the wheel 50 from or away from the axis of rotation of the wheel 41.

Referring more particularly now to details of the brush and its connecting structure, a flexible housing 80 is provided as part of the means G, which at its rear end is connected by means of a nut 81 to the externally screw threaded stub extension 82 through which the forward end 29 of the driven shaft D extends. A driven chain 85 extends longitudinally through this housing 80, which is of a flexible nature, including a plurality of relatively long links 86, which may be of wire or the like, and looped 80 at 87, at their ends, for universal jointed connection with similar loops provided upon adjacent links 86. At its outermost or forward end the flexible housing 80 has a cylindrical shaped hollow handle 89 fixedly mounted thereon, within which a bearing or bushing 90 is swiveled, and which is provided with a longitudinally extending passageway 91 therethrough rotatably receiving a socket connecting piece 92. At its rear end 90 92 is provided with a guide flange 95 to prevent forward longitudinal movement of the socket piece 92 outwardly of the handle bushing 90. At its extreme rear end the socket connecting piece 92 is provided with a hook or analogous element 95^a which is connected with the foremost link 86 of the driven chain 85. Integral with the bushing or handle piece 90 is a shield portion 98 which extends forwardly of the front edge 100 99 of the handle structure, and which is concavo convex in cross section, as is illustrated in Figure 4 of the drawings.

The brush head F includes a shank portion 101 adapted to have a detachable bayonet 105 jointed connection, at 102, with the forwardly projecting end of the connecting socket piece 92. This brush head 101 includes a body 105 having outwardly extending tufts 106 provided in spaced rows about the same. 110

The operation of the brush structure will be apparent from the foregoing description, and the brush head F may be electrically driven in either direction about its axis, depending upon whether the teeth in the upper or lower jaws are to be brushed. Dentists are in accord with the correct method of brushing teeth, which should be a one way brushing, and from the gums toward the outer edges of the teeth. With the type 115 of power driven tooth brush herein described this correct brushing of the teeth is rendered possible, and the brush head may be driven in the proper direction depending upon whether the inside or outside of the teeth are to be brushed, or the teeth in the upper or lower jaws are to be cleansed. The shield extending longitudinally at one side of the brush head not only guards the brush, but prevents splattering of foreign matter. The 120 125

reversible drive for the brush head prevents the tufts of brushes from wearing in one inclined direction, and are uniformly worn and maintained in their outstanding relation 5 incident to the fact that the brush is alternately used as the direction of rotation of the same is reversed.

Various changes in the shape size, and arrangement of parts may be made to the form 10 of invention herein shown and described, without departing from the spirit of the same or the scope of the claim.

We claim:

In a motor driven tooth brush the combination of a horizontally supported base, 15 a motor mounted on the base having a drive shaft vertically disposed in right angled relation with the base, a drive wheel on the shaft between the motor and the base, a relatively large wheel having a spindle extending 20 from one side thereof and being smooth and flat on the opposite side thereof, means rotatably supporting said spindle in the horizontal base with the relatively large wheel 25 horizontally supported above the horizontal base with its smooth flat side uppermost

and at its periphery in driven engagement with the peripheral edge of the motor wheel, a standard rigid with the base in right angled vertically upstanding relation therefrom, a driven shaft horizontally supported by said standard including a horizontal portion extending substantially diametrically across the relatively large wheel above the upper surface thereof in spaced relation, a friction wheel splined on the driven shaft above the relatively large wheel and at its periphery being in driven engagement with the upper surface of the relatively large wheel, the length of the driven shaft above 40 the relatively large wheel being such that the friction wheel may be slid diametrically across the relatively large wheel into engagement therewith at the opposite sides of the axis of rotation of the relatively large 45 wheel, and operating means slidably carried by the standard for moving the friction wheel and holding it in a desired engagement with the relatively large wheel for drive of the driven shaft.

GLEN WILLIAM BAIRD.
